CONTROL FOR PRESSING MACHINES

Otto H. Pearson, St. Joseph, Mich., and Ed Pearson, Salt Lake City, Utah, assignors, by mesne assignments, to Nicholas L. Strike, Salt Lake City, Utah

Application July 20, 1938, Serial No. 220,250

7 Claims. (Cl. 192—131)

Our invention relates to pressing machines, and more particularly to two-hand control pressing machines.

An important object of the invention is the provision in pneumatic means for operating such a machine, of a pilot valve, operable by relatively slight manual power, to actuate said pneumatic means and of pneumatic means to take up the wear of said valve.

10 In a machine of the character mentioned having three-position manuals for actuating the pilot valve, an object of the present invention is the elimination of spring means that moves the manuals from an intermediate to an inoperative position, and the elimination of spring means to maintain the manuals in a full operative position.

A still further object is to provide pneumatic means to withdraw the barrier from between the toggles of the manuals and flexible means employed to take up wear in the pilot valve.

In the drawings like reference characters designate similar parts in the several views.

Figure 1 is a side elevation of an embodiment 25 of my invention.

Figure 2 is an enlarged section taken on line 2—2 of Figure 1.

Figure 3 is a reduced elevation looking in the direction of arrow 3—3 of Figure 2.

30 Figure 4 is a reduced plan view similar to Figure 2, but showing the full operative position of the manuals.

Figure 5 is a view of the pilot valve stem removed from the valve casing.

35 Figure 6 is a broken enlarged section of the pneumatic driving cylinder for the press.

Figure 7 is a section through valve means for controlling the mechanism of the machine.

40 Figure 8 is a side elevation of a modified embodiment of my invention showing fluid means for controlling the barrier.

Figure 9 is an enlarged view of the head and finger for actuating the pilot valve showing resilient means for taking up wear of the valve.

45 Figure 10 is a modified manner of taking up wear of the valve and seat by using a diaphragm under air pressure.

Figure 11 is a sectional view of the valve casing enlarged to show the interior of the valve used to operate the cylinder for actuating the barrier shown in Figure 7.

50 Figure 12 is a sectional view of a modified form of the head and finger for actuating the valve with the air chamber shown in which a rubber

tube is used to actuate the take-up finger to take up wear of the valve and seat.

Figure 13 is a view showing the use of this chamber mounted to actuate the main valve.

Figure 14 is a view showing the means for providing fluid to the type of chamber shown in Figure 12 actuated by a separate control valve such as shown in Figure 8 for actuating the finger.

Referring more in detail to the drawings, the 10 reference number 10 generally designates the frame of the present machine, which supports a relatively stationary buck 12 and a pivotally mounted head 13. An arm 14, which supports the head 13, is pivotally mounted on the frame 15 at 15. The arm 14 is in turn pivotally connected with a link 16.

The link 16, together with a therewith pivotally connected link 17, form a toggle generally designated 18. The lower end of the link 17 has a 20 pivotal connection with a piston rod 19. A roller bearing 20, on the knuckle formed by the links 17 and piston 19, rides on a cam 21 having an upwardly inclined face 22 and a concave top face 23. A spring 61 may be coiled about the piston 25 rod 19, to cushion inward movement of the rod 19 into its cylinder hereinafter described.

One end of an oscillating tie bar 25 is pivotally mounted on a spindle 26 on the frame. The other end is connected with an offset stub shaft 24 at the elbow of the toggle 18.

A cylinder 27 has a ball and socket connection 28 with the frame of the machine, to permit oscillation of the cylinder. A piston 29 in the cylinder is mounted on the piston rod 19.

35 Heavy coil springs 30 and 31 tend to move the head 13 to the open position shown in Figure 1. The link 16 carries an ear 32 for reciprocating movement of a rod 33. A stop 34 on the rod 33 provides an abutment opposed to the ear 32, between which a spring 35, coiled about the rod 33, is disposed. An auxiliary spring 36 connecting with the frame and with the stop 34, may also be used. The springs 35 and 36 tend to move the rod toward the front of the machine.

45 Another stop 37 is disposed on the rod 33 on the other side of the ear 32 from the stop 34. The stop 37 may be in the form of a nut on a threaded portion of the rod 33, to permit adjustments of the stop 37. By this arrangement, movement of the ear 32 in one direction compresses the spring 35, tending to move the rod 33 forward, and movement of the ear 32 in the opposite direction causes it to strike the stop 37, effecting rearward movement of the rod.

45

50

55

A pipe 38 supplies air pressure, or other pressure fluid, to the machine. A manual valve 39 controls the flow therethrough. A branch 40 of the pipe 38 leads to a valve casing 41, hereinafter more fully described. The pipe 38 connects with a valve housing 42.

The housing has chambers 43 and 44 connecting by means of a passage 45. A ball valve 46 in one position closes the passage 45. A coiled spring 47 tends to move the ball valve 46 to said passage closing position. To aid in assembling, the chamber 43 is closed by a screw plug 48. A pipe 49 connects the chamber 44 with a passage 50 in head 51 of the cylinder 27. The passage 50 directs pressure fluid into the cylinder against the face of the piston 29, to urge the piston to the right in Figure 7.

An exhaust 52 connects with a chamber 53 in the valve housing 42. The chambers 44 and 53 connect by means of a passage 54, the walls of which passage provide a valve seat.

A valve 55, having a relatively slender pin 56 integral therewith, is disposed to reciprocate in the housing 42. The valve 55 when depressed engages the seat in the passage 54. When so depressed, the pin 56 pushes the ball valve 46 from its passage closing position, against the action of the coiled spring 47. Thus in said depressed position, the valve 55 closes the passage 54 and opens the passage 45, permitting fluid pressure to flow from the pipe 38, through the chamber 43, through the passage 45 through the chamber 44, and through the pipe 49 to the cylinder 27, to actuate the piston 29.

When the valve is released from said depressed position, the coiled spring 47 seats the ball valve 46 and through the intermediary of the pin 56 causes the valve 55 to move from its seat. In this position of the two valves, the flow of pressure fluid from the source to the cylinder is stopped, but since the chambers 44 and 53 are now connected, pressure fluid ahead of the piston 29 may pass through chamber 44, through passage 54, through chamber 53 and out at the exhaust 52.

A shell 57 has bolted between the complementary halves thereof, a diaphragm 58. A pin 59 fastened to the diaphragm reciprocates therewith. At the opposite side of the diaphragm 50 from the pin 59, the shell 57 receives pressure fluid from the pipe 60. It will be noted that the pin 59 is arranged to depress or actuate the valves 55 and 46 against the action of the spring 47.

The mechanism is actuated by a pair of spaced manuals 62 and 63. It is to be understood that the manuals are so spaced that they cannot be operated by a single hand, but require both hands of the operator to operate. This arrangement prevents the operator from getting his or her hands caught between the descending head 13 and the buck 12, which would injure and burn the operator's hands.

A table 64 is shown under the buck, and a flange 65 depends from the table. Openings 66 and 67 are arranged in the flange 65 to reach the ends only of the manuals 62 and 63 respectively.

The manuals 62 and 63 are pivoted at 68 and 69, which pivots are mounted upon a platform 70 beneath the table 64. A strap ties the pivots 68 and 69 together. Mounted rigidly on the manuals 62 and 63 and forming bell cranks therewith are arms 72 and 73 respectively. Stops 74 and 75 limit outward movement of the arms 72 and 73. The bolts 100 rigidly fasten the arms

72, 73 to the manuals 62 and 63 respectively. The bolts 100 are not pivots.

A whippletree 75 is fastened at its ends to the arms 72 and 73, by means of links 76 and 77 respectively. The whippletree adjacent its midpoint, carries a head 78 which is pivotally connected to the whippletree. The head 78 has a cylindrical recess for an air cylinder 79.

A finger 80 has a piston head 81 in the cylinder chamber 79 of the head 78. The head member 78 itself limits the outward movement of the finger head 81, and the inward movement of the finger is limited by the air or fluid in the cylinder 79.

A pilot valve 82 is mounted in a tubular sleeve 82a and the stem is engaged by the end of the stem 80 which valve engages in the seat in the end of the exhaust chamber 89. The nut 84 is screwed onto the stem 82a to lock the valve casing 41 and component parts to the bracket 72a 20 supporting it from the platform 70. The platform 70 is made of either solid or flexible material, that shown being flexible spring steel so that if desired the resilient means may be utilized in the platform 70.

The nose of the valve 82 is elongated as shown at 85, and engages a ball valve 86. The air pressure in the chamber 91 behind the ball valve 86 urges same against its seat in the casing 41. When the valve 82 is moved inwardly relative to the casing 41, the ball valve 86 is moved from its seat against the air pressure in the chamber 91.

The valve casing 41 has a chamber 88 that is provided with exhausts 89. The pipe 60 connects with a chamber 90 in the casing 41. The pipe 40 connects with a chamber 91 also in the casing 41.

A pipe 92 is connected to a T-coupling and in time to a pipe 92a which is then connected to the head 78 into the cylinder 79 to provide air pressure to take up wear of the valve 82. The other connections of the T are either closed or may be connected with other machines if tandem connections of machines is desired.

The nose 85 of the valve 82 fits loosely in the casing whereby fluid pressure may pass around same at all times. The chamber 88 and 90 and chambers 90 and 91 are connected by the passages in which the nose 85 loosely fits. A screw plug 93 closes the end of the casing 41 in the end of the chamber 91.

When the air pressure in the chamber 91 is seating the ball valve 86 upon its seat (which is its normal position when the manuals are in the full line positions, shown in Figure 2,) the flow of pressure fluid from the source is stopped. Moreover, in this position the exhausts 89 are connected with the diaphragm shell 57, whereby the diaphragm may be moved by its spring 94 60 to the position shown in Figure 7, releasing the valve 55.

When the valve 82 is moved inwardly relative to the casing 41, the taper of the valve 82 seats and thus seals the passage between the chambers 88 and 90, thereby shutting off the exhausts. At the same time the ball valve 86 is unseated, connecting the chambers 90 and 91 and thereby permitting fluid pressure to flow from the pipe 40 to the pipe 60, thus actuating the diaphragm 58, which in turn operates the main supply valve 46. It will thus be seen that the valve 86 acts as a pilot valve, requiring only relatively slight pressure to operate the main valve 46 of the machine.

To temporarily limit movement of the arms 72 and 73 toward each other, a barrier 95 is provided. It is in the shape of a bell crank 96 pivoted at 97. The rod 33 connects with the lower end of the bell crank 96 to move the barrier 95 to and from a position between the arms 72 and 73. The barrier is beveled to force the arms 72 and 73 apart (from the position shown in Figure 4) when the barrier is moved between them. The arms 72 and 73 have a limited movement between the stops 74 and 75 and the barrier.

To initiate the operation of the present invention, both manuals 62, 63 must be moved from the full line to the broken line positions shown in Figure 2. If only one manual is so moved, the whippetree 75 is turned upon the head 78 without moving said head appreciably.

When both manuals are moved to the broken line positions, the head 78 is advanced to the right in Figure 2. This movement causes the finger 80 to actuate the valve 82, which opens the pilot valve 86 in the manner described hereinbefore. The pressure fluid then actuates the diaphragm, which opens the main valve 46 as explained hereinbefore. Fluid pressure is thereby admitted to the cylinder 27, thus driving the piston 28.

The force against the piston moves the roller bearing 20 up the inclined face 22 and then around the concave face 23. This movement causes the closing of the head 13 down upon the buck 12, as shown in broken lines in Figure 1, against the action of the springs 30, 31.

During the foregoing operation, the arms 72, 73, may be against the sides of the barrier 95. If, prior to the time the head 13 engages the buck 12, the operator releases either hand, the whippetree is turned, or if both hands are released, the force upon the whippetree is released. In either event, there is nothing to maintain the pilot valve 86 off its seat. When said valve is seated, the flow of fluid pressure is checked, releasing the main valve 46 and permitting same to be seated, which checks the pressure flow to the cylinder 27. Since the cylinder is then connected with the exhaust 52, the large coil springs 30, 31 may and do return the head to the open, full line position shown in Figure 1.

By the time the head 13 engages or substantially engages the buck 12, the ear 32 has engaged the nut 31, thus drawing the rod 33, which withdraws the barrier from between the arms 72, 73. The operator may then move the manuals to the locked position shown in Figure 4. The locked position is the over-center or past center position of the arms 72, 73 and the links 76, 77, which arms and links respectively form opposed toggles. In this position, the operator may remove his hands from both manuals and the head 13 will remain in pressing engagement with the buck 12.

To raise the head 13, all that is necessary is to release either manual or both manuals. The manuals float in the inoperative or rest position designated by the full lines in Figure 2. This machine is marked by the absence of spring means to maintain the manuals in the full operative position (Figure 4), and by the absence of spring means that moves the manuals from the intermediate (broken line position in Figure 2) to the inoperative position.

The air pressure in the chamber is only to compensate for wear of the valves 82 and 86 and their seats and is not adapted to perform the function mentioned earlier in this paragraph.

Upon release of either manual or both manuals, the fluid pressure is cut off, the pressure in

the cylinder is exhausted, allowing the springs 31, 32, to raise the pressing head 13. At the same time the ear 32 moves away from the stop 37, thus releasing the rod 33 and allowing the springs 35, 36 to move the barrier up between the arms 72, 73. 5

Constant pressure is maintained behind the piston 81 by the pressure in the line 40 passing through the line 92a thus the piston is maintained in its full stroke position and the only movement ever permitted is when the whippetree 10 has been moved to the full operating position, the air in the cylinder and partially in the line will then be compressed sufficient to take up wear in the valve 82. 10

In Figure 8 of the drawings the valve mechanism shown in Figures 1 and 7 is eliminated and the manuals control the valve 86 which controls the air flow through the line 101 to the cylinder 27 making a direct air control and thus simplifying the operation of the device and the number 20 of valves required to control the mechanism. The barrier 95 in this view is shown as controlled by an air cylinder 102 mounted to the frame of the device and operating a shaft 33a which in turn is attached to the lower end of the bell crank 96. 25 An air line 103 connects the cylinder 102 with a valve 104 in a valve casing mounted to the frame 10 and the valve is controlled by an adjustable stem 105. This stem is controlled and actuated by a boss 106 on the side of the toggle member 16 thus when the toggle has reached a near vertical position and the head 13 has been brought down to the bed member 12 or near thereto the stem 105 is engaged with the boss 106 and the valve 104 is operated which causes air from the line 107 30 to flow through the valve chamber and the line 103 to the cylinder 102 driving the piston therein toward the end of the cylinder and withdrawing the barrier. When the machine is released the valve stem is released by the withdrawal of the 40 toggle and the air is exhausted from the exhaust ports 108. 35

Another form of operating the cylinder 102 is that of having a pipe leading from the main power cylinder 27 to permit passage of air from the power cylinder 27 through the pipe into the cylinder 102 when the piston has traveled a predetermined distance of its stroke. A spring s in the cylinder 102 returns the piston to the initial position when the valve is released and air exhausted to again insert the barrier between the arms 72 and 73. 50

In Figure 8 we have shown the use of a rubber or resilient member 109 filling the cylinder 79 and at all times forcing the head of the piston 81 55 toward the end of the cylinder but allowing for slight contraction thereof to take up any wear of the valve 82 and its respective seat.

Figure 10 shows a still further modified manner of taking up this wear constituting the same member 78 and finger 80 but with the finger 80 pressing against one side 110 of a double diaphragm chamber 111, said chamber to be filled with constant air pressure from the line 112 and with the diaphragm 113 engaging the valve 82. 60

In Figure 11 we have shown a sectional view of the control valve 104 with the ball valve shown as 104, the inlet pipe as 107, and the line 103 leading to the cylinder 102. This is the same valve as shown in Figure 8 showing the details 70 thereof.

In Figures 12, 13 and 14, we have shown another method of taking up the wear of the valve in the main control valve. In Figure 13 the valve is shown as 82a and the ball valve as 86a, carried 75

in the casing shown as 41a. The stem 82a in this particular type of device is provided with adjustable control nuts shown as 119a which nuts are engaged by the annular flange 119 of the 5 head 115. Within the head 115 there is a cylindrical chamber 116 carrying a rubber bladder or inner tube 117 with the air line 92 leading thereinto and with the piston of Figure 1 replaced by a stem 118 provided with a head inside the chamber. Thus, when the head 115 is actuated by the whippletree 75 the annular flange engages the nuts 119a and actuates the valve and when the valve has been opened and the pressing buck 10 actuated the air passes through the line 92' and 15 expands the inner tube forcing the stem 118 against the stem of the valve 82a to take up wear of the valve.

In Figure 14 this particular type of head is shown connected to the valve 104 as shown in 20 Figure 8 so that the air is supplied to the tube 117 through a line 120 when the stem 105a has been engaged by any movable part of the machine such as the toggle links 16 or the boss 106. This 25 particular valve 104 might be actuated by the buck arm 14 or any other movable part of the machine which moves when the movable buck is brought into contact with the stationary buck.

It will be obvious that the line 120 may be 30 connected directly into the line 103 of Figure 8, if desired.

We have also found that the pressure required to break or crack the valves from their seats should be less than the amount of pressure required to bend any of the resilient parts or 35 compress any of the resilient means employed in our several devices to seat the valves and follow up the wear of any of the various valves shown in our drawings.

As shown in Figure 3 the plate 70 may be made 40 of resilient material to yield when the manuals are operated from intermediate to full operative position to take up any wear of the exhaust valve 82. Also the studs 68 and 69, the arms 72 and 73 and the links 76 and 77, the head 75 45 or the support bracket for the valve casing 41 may be made of some resilient medium if desired to take the wear of the valve 82 or its seat. It will be obvious that the valves 82 and 86 may be made of resilient material such as rubber or 50 like material to take up any wear and that the seats in which the valves seat may also be made with rubber inserts for this same reason.

There are three positions of the manuals as used in this invention, namely: inoperative, intermediate, and full operative positions. The 55 inoperative position is that position maintained when the manuals are idling and the device is not in use, as shown by the full line position in Figure 2. The intermediate position is considered that position to which the manuals are moved, from the inoperative position by the operator to cause movement of the head against the head member or near thereto but is not sufficiently advanced to engage the tension of the 60 stem 80 against the valve 82 an amount greater than just to crack the valve 86 and is not sufficient to compress or utilize the air in the chamber 79. The full operative position is that position 65 shown in Figure 4 of the drawings where the manuals have been advanced sufficient distance to throw the toggle links beyond dead center locking the manuals in the full operative position at which time the operator may remove the hands and leave the machine until it is desired to release it. It will further be seen that the operation 70

of the machine is in two steps, (a) the manuals are movable from the full line position, or inoperative position to the intermediate position which brings the head to engage the bed, and (b) the manuals are movable from the intermediate 5 position to the full operative position locking the head to the buck. The first step lowers the head into contact with the buck and the second step locks the manuals with the head in contact 10 tacting pressing engagement.

While we have illustrated and described what we now regard as the preferred embodiment of our invention, the construction is, of course, subject to modification without departing from the spirit of our invention. We therefore, do not 15 wish to restrict ourselves to the particular form of construction illustrated and described, but desire to avail ourselves of all modifications which may fall within the scope of the appended claims.

Having thus described our invention we desire 20 to secure by Letters Patent and claim:

1. A pressing machine comprising head and bed members, at least one of which is relatively movable; operating mechanism therefor; and control means for said mechanism, including 25 spaced manuals, movable from inoperative to intermediate position to substantially draw the head member to the bed member and thereafter to the full operative position; means governed by the relative position of the head and bed members 30 controlling movement of the manuals from intermediate to full operative position; a source of pressure fluid connected with said operating mechanism; a single valve controlled by the combined movement of said manuals; and resilient means to take up wear of the valve and the 35 valve seat in the operative mechanism.

2. A pressing machine comprising head and bed members, at least one of which is relatively movable to and from the other; operating mechanism therefor; and control means for said mechanism including spaced manuals, movable from inoperative to intermediate position and thereafter to full operative position; a barrier controlled by the relative position of the head to the 45 bed member to control the movement of the manual from the intermediate position to the full operative position a valve mounted in the path of the operating mechanism to be actuated thereby; and a hydraulic cylinder to control the position of the barrier.

3. A pressing machine comprising, head and bed members one of which is movable to and from the other; operating mechanism for said movable member; and control means for said 55 mechanism including spaced manuals, movable from inoperative to intermediate position to actuate the movable member to near the other member and thereafter to full operative position to lock the movable member into pressing contact 60 with the other member; a source of fluid pressure for operating said mechanism; a pilot valve for controlling said fluid pressure; a whippletree actuated by said manuals to allow one of the other of said members to be pressed inwardly 65 without effecting movement of said movable member but to be actuated when both manuals are operated; a slide head attached to and operated by said whippletree; a cylinder in said head; means to introduce into said cylinder, fluid 70 pressure, to maintain a constant pressure in said cylinder; and a piston in said cylinder having the stem extended out and adapted to engage the pilot valve stem when the whippletree has been operated.

4. A pressing machine as set out in claim 3, including a barrier hydraulically controlled by the relative position of the head and bed member, said barrier to be inserted to prevent movement beyond intermediate position of the manuals until the movable member has reached a safety position for the operator.
5. A pressing machine comprising head and bed members, one of which is movable to and from the other; operating mechanism for said movable member; and control means for said mechanism including spaced manuals; a valve control for fluid pressure for moving said movable member; toggle arms attached to and operable by said manuals; a whippertree movable by said arms; a barrier adapted to be brought into position between said arms to prevent further inward movement thereof when the manuals have been moved from inoperative to intermediate position, said barrier being controlled by the relative position of the head and bed members and to be withdrawn when the movable member

has reached a predetermined position to permit further overcenter movement of said toggle arms to lock the manuals in the full operative position; and resilient means to control the said valve.

6. A pressing machine as set out in claim 2, including a valve operated by the manuals to control the operating mechanism; and resilient means to take up the wear of said valve.

7. In a control mechanism for pressing machines, the combination of spaced manuals; toggle lever devices connected with the end of each manual; a whippertree connected with the ends of said toggle lever devices; a sliding head pivotally mounted medially of said whippertree; a fluid pressure cylinder in said head; a piston in said cylinder with the stem extending from the end of the head; means to connect the cylinder with a source of fluid pressure; and a pilot valve to be controlled by said piston stem.
